UNITED STATES PATENT OFFICE.

ARTHUR BURROUGHS EVANS, OF LEEDS, ENGLAND.

AUTOMATIC FEEDING MECHANISM FOR SHEET-PRINTING MACHINES.

Application filed September 3, 1924, Serial No. 735,680, and in Great Britain November 7, 1923.

This invention relates to automatic feeding mechanism for sheet printing machines.

In sheet printing machines having automatic feeding mechanism, it has been customary for the sheet to be taken automatically from the pile and to be delivered into the control of rubber runners and rollers, or rollers, or tapes, or the like, by which it is run forward and is registered to a proper position from which it is carried to printing contact by grippers or the like which are integral elements of the printing machine.

Thus it is generally necessary for at least a clear length of the sheet to be interposed between the registering mechanism and the automatic feeding mechanism, in order to give room for registration.

The invention has for its object to provide automatic feeding mechanism such that the travel of the sheet and the space required for the mechanism are greatly reduced.

The invention is particularly applicable in those cases in which the sheet requires to be turned over end for end on leaving the pile and to be gripped by a gripper on the impression cylinder or the like, operating to take the sheet to the impression cylinder as it lies with its leading edge under this cylinder, being the usual method understood to be meant by the term "under-fed."

According to the invention I register the sheet to front- and side-lays or the like whilst it is the top sheet of the pile, and seize the sheet in suction grippers of well-known form by which means the edge of the sheet is lifted and turned over and carried forward towards the impression cylinder or the like.

According to this invention, moreover, I constrain the nozzle end of such suction grippers to travel by a reciprocatory motion in an epicyclic path at varying and suitable speed, by means of cams and levers or the like operating upon the axis of wheels or the like which carry such suction grippers, and which wheels are also constrained to rotate by being geared to circular segments coaxial with the fulcrum axis of such levers or the like, so that any axis carried by such wheels and therefore the ends of the nozzles of the grippers, follow a reciprocating epicyclic path.

According to this invention moreover this epicyclic path is situated tangentially

to the path of the gripper of the impression cylinder or the like, and the suction grippers are made to release the sheet and the grippers of such impression cylinder to take the sheet at the line of contact of such paths.

According to this invention, moreover, the sheet is made to travel at the same speed as the impression cylinder or the like at the time of such release.

By the means described register of the sheet in the printing machine is obtained without recourse to a separate registering mechanism and a sheet length is saved in the space occupied by the combined machines.

The invention is hereinafter described with reference to the accompanying drawings in which—

Figure 1 is a detail view in side elevation of the mechanism for effecting registration of the uppermost sheet at the top of a pile of sheets.

Figure 2 is a detail view in elevation similar to Figure 1 showing the parts of the mechanism in the position occupied when the uppermost sheet has been registered.

Figure 3 is a detail plan view of the mechanism represented in Figures 1 and 2.

Figure 4 is a side elevation of the automatic feeding mechanism according to the invention, the parts being shown in the disposition occupied at the beginning of the feed movement.

Figure 5 is an elevation similar to Figure 4 showing the parts of the mechanism at the moment of the completion of the feed movement.

Figure 6 is a detail view of the mounting of the suction nozzles for effecting the transfer of the sheet to the impression cylinder.

In carrying the invention into effect according to the construction illustrated in the accompanying drawings, and referring especially to Figures 1-3, a front lay α is mounted upon a horizontally disposed rod b in a position adjacent the upper end of the pile of sheets c . A sleeve d slidably mounted upon the rod b is fitted with a rack d^1 adapted to engage with a toothed pinion e^1 fixedly mounted upon a transverse shaft e adapted to receive an oscillatory movement from a moving part of the printing machine, through such means as an arm e^2 and connecting rod (not shown).

- The suction head or nozzle f is provided upon a tubular member f^1 which is pivoted to the sleeve d on a horizontal axis by a pin f^2 carried in lugs d^2 upon the said sleeve d .
 5 The tubular member f^1 is connected to a tube f^3 by which suction is applied and which is provided with a valve adapted to operate automatically to shut off the suction immediately the suction nozzle f has registered the
 10 uppermost sheet in the pile of sheets. The tubular member f^1 carries a laterally projecting pin f^4 and the sleeve d has pivoted upon it an arm g formed at the outer end with a recess to receive the pin f^4 . The arm
 15 g carries a rotatably mounted lug g^1 in which is fitted a rod g^2 disposed substantially parallel with the rod b and passing freely through a collar b^1 adapted to be secured in a determined position of adjustment upon
 20 the rod b by a screw stud or bolt b^2 . A spring g^3 is carried upon the rod g^2 between the lug g^1 and the collar b^1 and adjusting nuts g^4 are mounted upon the end of the rod g^1 protruding beyond the collar b^1 .
 25 The front lay a carries a cam surface a^1 adapted to raise the suction nozzle f from the level of the upper surface of the pile of sheets when the nozzle f is in its rearmost position, and a spring h , maintained in position by pins f^5 , d^3 , provided respectively upon the tubular member f^1 and the sleeve d , serves to press upon the tubular member f^1 in such manner as to maintain it in contact with the cam a^1 and thus to press it
 30 downwardly for engagement with the pile of sheets when it is moved into the forward position.
 35 The mechanism for automatically feeding the sheet which has been registered against the front lay a by the mechanism hereinbefore described, comprises a series of suction nozzles i upon a tube or hollow shaft i^1 carried by a pair of hollow arms i^2 mounted upon a hollow shaft j which is rotatably fitted in the upper ends of the longer arms of two bell-crank levers k which also are provided hollow and connected to suction pipes k^1 through which suction may be applied to the said nozzles i and which pipes are provided with valves automatically operated for the control of the suction according to the operation of the mechanism.
 40 The bell-crank levers k are pivoted upon shafts l^1 disposed at opposite sides of the pile of sheets, and the short arm of each lever has connected to it a spring k^2 tending to draw the short arm in the downward direction. A second bell-crank lever l is mounted fixedly upon each shaft l^1 and has the shorter arm connected to a spring l^2 tending to draw it downwardly. A toothed segment m is also fixedly mounted upon one of the shafts l^1 and engages with a pinion m^1 mounted upon the hollow shaft j . The
 45 impression cylinder n to which the sheets

are to be delivered is geared to a shaft o by means of similar toothed wheels n^1 , o^1 . The shaft o has fixedly mounted upon it cams o^2 , o^3 . A shaft p disposed parallel with and above the shaft o has loosely mounted upon it two pairs of levers p^1 , p^2 which are respectively connected at their lower ends through slide blocks p^3 , p^4 with the bell-crank levers k and l , while the said levers further carry runners p^5 and p^6 adapted to bear respectively upon the cams o^2 and o^3 .
 70

Adjustable stops q serve to limit the reciprocatory movement of the segment m for the purpose of determining the extreme limits of the movement of the suction nozzles i .
 80

The operation of the mechanism hereinbefore described is as follows:—

The pile of sheets c being in position, upon the oscillation of the shaft e , the sleeve d is moved forward along the rod c carrying the nozzle f and the tubular member f^1 with it, the pin f^4 being engaged with the arm g . When the nuts g contact with the collar b^1 the forward movement of the arm g is arrested and the suction nozzle f is permitted to fall upon the pile of sheets c by disengagement of the pin f^4 from the arm g . At this moment the suction is applied through the pipe f^3 . On the return movement of the shaft e the suction nozzle and tubular member f^1 are carried rearwardly by the sleeve d , the nozzle adhering to the uppermost sheet of the pile c . This movement continues until the sheet contacts with the front lay a and the nozzle f begins to ascend the cam a^1 .
 100 At this moment the suction is interrupted. The upward movement of the suction nozzle f permits the re-engagement of the arm g with the pin f^4 under the action of the spring g^3 .
 105

The uppermost sheet having been registered it is now transferred to the impression cylinder n by the nozzles i , the rotation of the cam shaft o serving to oscillate the levers k and l and the toothed segment m in such manner that the nozzles i describe an epicyclic path, carrying the sheet of paper with them. The epicyclic path is tangential to the circumference of the impression cylinder so that the sheet of paper is thus transferred to the grippers n^2 on the said impression cylinder n .
 110

Similar mechanism to that hereinbefore described for use in securing front registration of the sheet may be provided to effect side registration but any suitable alternative construction of side lay mechanism may be adopted.
 115

It will be understood that the invention is not limited to the construction of the parts of the mechanism hereinbefore described.
 120

I claim:

1. Automatic feeding apparatus for sheet printing machines consisting in combination
 125

130

of a movable suction nozzle adapted to engage the topmost sheet of a pile of sheets, means for moving the suction nozzle synchronously with the printing machine cycle 5 for moving the topmost sheet engaged by it upon the pile into position on the pile in register, a stop against which the said topmost sheet is brought into register and separate means for transferring to the printing 10 position the topmost sheet on the pile from the position in which it has been brought into register thereon, substantially as described.

2. Automatic feeding apparatus for sheet printing machines comprising means for registering the sheet to be fed into printing position, and suction grippers by which the sheet in register is raised, turned over and carried forward from the position in which 15 it has been brought into register into the printing position, substantially as described.

3. Automatic feeding apparatus for sheet printing machines consisting in combination of a movable suction nozzle, means for moving the said suction nozzle to bring the sheet to be fed into register, and suction grippers by which the sheet in register is engaged, raised, turned over and carried forward to the printing position, substantially as described. 20

4. Automatic feeding apparatus for sheet printing machines consisting of a suction nozzle, a reciprocating member upon which the said suction nozzle is pivotally mounted, 25 means for imparting reciprocating movement to the said reciprocating member synchronously with the printing machine cycle, a stop against which the topmost sheet of a pile of sheets is brought into register by 30 the said suction nozzle in its movement, and means for transferring to the printing position the said topmost sheet from the position it has been brought into register, substantially as described.

5. Automatic feeding apparatus for sheet printing machines consisting of a suction nozzle, a reciprocating member upon which the said suction nozzle is pivotally mounted, means by which the suction nozzle is brought 35 into an elevated position on its return movement, means by which it is maintained in that position on its next forward movement, means for imparting reciprocating movement to the said reciprocating member synchronously with the printing machine cycle, 40 a stop against which the topmost sheet of a pile of sheets is brought into register by the said suction nozzle in its movement, and means for transferring to the printing position the said topmost sheet from the position it has been brought into register, substantially as described.

6. Automatic feeding apparatus for sheet printing machines consisting of means by 45 which the sheet to be brought into printing

position is first brought into register, suction grippers for engaging the said sheet, and means by which the said suction grippers are operated to raise, turn over and carry forward the said sheet to the printing position whereby the said suction grippers are moved in an epicyclic path, substantially as described. 70

7. Automatic feeding apparatus for sheet printing machines comprising means for bringing into register the sheet to be fed into printing position, suction grippers by which the said sheet is engaged, means by which the said suction grippers are moved to raise, turn over and carry forward the 75 said sheet to the printing position comprising members upon which the said suction grippers are mounted and to which movement in an epicyclic path is imparted, substantially as described. 80

8. Automatic feeding apparatus for sheet printing machines comprising means for bringing into register the sheet to be fed into printing position, suction grippers by which the said sheet is engaged, means by 85 which said suction grippers are moved to raise, turn over and carry forward the said sheet to the printing position comprising members upon which the said suction grippers are mounted and to which movement in 90 an epicyclic path is imparted, an impression cylinder, grippers mounted on the said impression cylinder with respect to whose path the said epicyclic path is tangential, and means for causing the suction grippers to 95 release the sheet and for the grippers of the said impression cylinder to take the sheet at the line of contact of the said paths, substantially as described. 100

9. Automatic feeding apparatus for sheet printing machines comprising means for bringing into register the sheet to be fed into printing position, suction grippers by which the said sheet is engaged, means by which the said suction grippers are moved 105 to raise, turn over and carry forward the said sheet to the printing position comprising members upon which the said suction grippers are mounted and to which movement in an epicyclic path is imparted, an impression cylinder, grippers mounted on the 110 said impression cylinder with respect to whose path the said epicyclic path is tangential, means for causing the suction grippers to release the sheet and for the grippers 115 of the said impression cylinder to take the sheet at the line of contact of the said paths, and means for imparting to the sheet on its release by the said suction grippers the same speed as the impression cylinder at the time 120 of such release, substantially as described. 125

10. Automatic feeding apparatus for sheet printing machines consisting in combination of means for bringing into register the sheet to be passed to the printing position 130

tion and suction grippers by which the said sheets are transferred to the impression cylinder, rotary elements upon which the said suction grippers are mounted, said rotary elements being carried by reciprocating members, oscillatory segmental members engaging the said rotary elements, the axes of the

said oscillatory segmental members coinciding with the axes of the said reciprocating members, and means whereby the sheet ¹⁰ is engaged in the impression cylinder at the time of its release from the suction grippers, substantially as described.

ARTHUR BURROUGHES EVANS.
